AUTOMATIC MOTOR CONTROL UNIT

Walter W. Hensler and George B. Mann, Indianapolis, Ind., assignors to Howard W. Sams & Co., Inc., Indianapolis, Ind., a corporation

Application December 21, 1955, Serial No. 554,552

1 Claim. (Cl. 318—207)

This invention relates generally to systems for rotating radio or television antennas, and more particularly it relates to a remote control system for rotating television and radio antennas wherein an antenna may be controlled at one or more points remote from the antenna.

Television receivers and high-frequency radio receivers are provided with directional antennas which can be located at points remote from receivers and rotated by means of so-called control heads located adjacent to each receiver and operable to drive an antenna rotating motor in any desired direction. If a home is provided with a single television receiver, the control head for the directional antenna can be located adjacent to the receiver and there is no particular problem. Where a home is provided with two or more television receivers and a single directional antenna, it then becomes necessary to provide a means of controlling rotation of the antenna from each individual receiver. It is conventional practice to provide socket means at each receiver so that a single control head can be moved from one receiver to another and utilized to control rotation of the antenna from any single receiver. This entails appreciable inconvenience because the different receivers in a home may be rather widely separated and when one given receiver is to be operated it is oftentimes necessary to go to one of the other receivers, pick up the control head and move it to the particular receiver which is to be used.

The principal object of this invention is to provide an antenna rotating system, wherein a control head may be located permanently at each television receiver.

Another object of the invention is to provide an antenna rotating system for controlling an antenna from a plurality of remote receivers, each receiver having a control head operable to exercise sole and complete control of the antenna.

Still another object of the invention is to provide an antenna rotating system for controlling an antenna from a plurality of remote receivers, wherein the antenna may be controlled from one receiver at a time without causing any sort of damage to the antenna rotating motor or to other portions of the antenna rotating system.

In accordance with this invention, there is provided an antenna rotating system comprising a reversible antenna motor, a first control head located at one receiver for controlling rotation of said motor, and a second control head located at another receiver and including switching facilities adapted to disable said first control head and to connect said second control head in operative relation with said motor.

The full nature of the invention will be understood from the accompanying drawings and the following description and claim.

Fig. 1 is a schematic diagram illustrating a home having a plurality of television receivers adapted to operate from a single antenna; and

Fig. 2 is a circuit diagram of the antenna rotating system utilized for controlling an antenna from the plurality of receivers illustrated in Fig. 1.

2

Referring to the drawings, this invention is applicable where it is desired to utilize a single directional antenna for a plurality of individual television or radio receivers, as illustrated in Fig. 1. For example, a home 10 may have a first receiver 11 located in a first floor room, a second receiver 12 located in the basement, and a third receiver 14 located on the second floor of the home. Receivers 11, 12, and 14 may be coupled to a single cable 15 leading to the antenna 16 and its rotating motor 17. In order to control motor 17 from each receiver, there are provided at each receiver, control heads 18, 19, and 20, each of which may be coupled into the motor control conductors within cable 15. By means of this arrangement, any one of the receivers 11, 12, and 14 may be operated and the antenna 16 may be rotated from any one of the receivers.

Referring to Fig. 2, there are provided the control heads 18, 19, and 20. Each of these control heads is identical in all respects. The control head 18 is illustrated in detail and it will be understood that the structures of heads 19 and 20 are identical therewith. The head 18 includes a transformer, the primary 22 of which may be connected to a commercial source of power 23 through a single-pole, double-throw section 24 of a motor reversing switch 25.

The secondary winding 26 of the transformer may be connected to either of the conductors 27 and 28 of cable 15 through a second single-pole, double-throw section 29 of reversing switch 25. The secondary winding 26 may also be connected to a common return conductor 30. A tap may be taken off an intermediate point 31 of secondary winding 26 and connected through an indicator 32 to conductor 33 of cable 15. This control head may be considered as a main control head since it performs no switching function and is the control head which normally exercises control of the antenna motor.

Control head 18 may be connected through conductors 27, 28, and 33 to the normally closed contacts 35, 36, and 37, respectively, of a relay switch 38. The tongues 40, 49, and 41 of switch 38, in turn, may be connected through cable 15 with normally closed contacts 42, 43, and 44 of a second relay switch 45. The tongues 46, 47, and 48 of switch 45 may, in turn, be connected by cable 15 with the windings of an antenna rotating motor 17 and a control potentiometer 49 connected between motor 17 and return conductor 30. The switches 38 and 45 are normally closed to connect control head 18 with motor 17, whereby operation of switch 25 rotates motor 17 in one direction or the other depending upon the position of switch 25.

Control head 19 may be connected with the normally open contacts 50, 51, and 52 of switch 38 by means of conductors 53, 54, and 55, respectively. Conductors 53 and 54 correspond with conductors 27 and 28 in that they are connected with the motor-reversing switch 25 of head 19. The operating coil of relay switch 38 may be connected to conductors 53 and 54 through the electrolytic capacitors 56, 57, and 58, respectively, whereby switch 38 may be energized from switch 25 in control head 19, regardless of the direction of rotation of motor 17. Switch 38 may be connected through conductor 59 with the return conductor 30, whereby switch 38 may be energized from the secondary winding 26 of the transformer in head 19.

The electrolytic capacitors 56, 57, and 58 are utilized for the purpose of energizing switch 38 from either of the lines 53 and 54 without the need of making switch 38 a polarized relay. Capacitors 56, 57, and 58 are also designed to provide a resonant circuit, including relay 38, whereby maximum current and minimum power will be utilized for operating relay 38.

Control head 20 is connected to the normally open contacts of switch 45 in identically the same manner as described in connection with control head 19. Accordingly, no detailed description of this circuit is deemed to be necessary.

In operation, it may first be assumed that it is desired to operate television receiver 11. Switch 25 may be operated to close the power circuit through primary winding 22 through section 24 thereof, while section 29 connects secondary 26 with either conductor 27 or conductor 28. 10 Indicator 32 will show the direction of rotation of antenna motor 17 and antenna 16 and if the television signal appears to decrease in intensity, switch 25 may be operated to reverse motor 17. When the maximum signal is attained, switch 25 may be opened to stop motor 17.

If it is desired to operate television receivers 12 or 14, then control heads 19 or 20, respectively, may be operated to rotate antenna 16. It may be assumed that control head 19 is operated and in this case operation of its reversing switch 25 closes a circuit from transformer secondary 26 through conductors 53 or 54, capacitors 56 or 57, capacitor 58, the winding of relay 38, and conductors 59 and 30, respectively, back to secondary 26. Relay switch 38 is energized to close tongues 39, 40 and 41 with normally open contacts 50, 51, and 52, respectively. Control head 18 is disconnected at the open contacts 35, 36, and 37, and motor 17 is controlled from switch 25 of control head 19 in the same manner as described in connection with control head 18. Since control head 19 automatically disconnects control head 18, there can be no damage to control head 18 even though a second person may attempt to tune in receiver 11 associated therewith.

Control head 20 may be operated to energize relay switch 45 opening contacts 42, 43, and 44 and closing the normally open contacts connected with the head 20.

Thus, control head 20 may be utilized to control motor 17 from receiver 14. As in the case of head 19, the relay switch 34 disconnects heads 18 and 19 so that attempted operation of these disconnected heads cannot cause any damage to them.

5 From the foregoing description, it will be apparent that this invention provides an antenna-rotating system, wherein an antenna-rotating motor may be controlled from any one of a number of remote points. The system includes facilities which prevent damage to the control heads themselves as well as to the antenna-rotating motor.

The invention claimed is:

15 An antenna-rotating system comprising a reversing motor having a pair of windings, a power supply line coupled to said motor windings, a first control head including a reversing switch means in said line for connecting a power source to either one of said windings, a second control head including a reversing switch means 20 for connecting a source of power to either one of said windings, and a relay switch means including normally closed contacts coupled to said first control head and normally open contacts coupled to said second control head, said relay means including switching tongues coupled to said windings and normally closed with said normally closed contacts, and a relay winding coupled to said reversing switch means of said second head for energization thereby to open said normally closed contacts and to close said normally open contacts.
